UNITED STATES PATENT OFFICE

2,611,014

ACTUATED CHRISTMAS TREE ORNAMENT

Leslie D. Burgess, Chicago, Ill., assignor to
Wells, Inc., a corporation of Illinois

Application September 6, 1950, Serial No. 183,390

9 Claims. (Cl. 177—7)

1

This invention relates to an actuated ornamental unit and more particularly to an actuated bell ringing unit adapted to be self-supporting and connected to the ordinary light socket of a Christmas tree light strand.

An object of this invention is to provide a new and improved actuated bell ringing unit of the character described.

Another object is the provision of novel means for attaching the unit to a limb of the tree or the like to hold the unit in upright position.

Another object is the provision of means for supporting the operating structure of the unit removably within a housing.

Another object is the provision of novel means for cooling the operating structure of the unit.

Another object is the provision of structure for supporting the bell in such a manner as to prevent the core of the operating solenoid from removing itself therefrom during operation of the device.

Other objects and advantages will be apparent from the following description taken in connection with an embodiment of the invention shown in the drawings, in which:

Fig. 1 is a diagrammatical view of a Christmas tree showing a light strand thereon and the unit of this invention; Fig. 2 is an elevational plan view of the unit; Fig. 3 is a top plan view; Fig. 4 is a bottom view; Fig. 5 is a sectional view taken through the approximate center of the unit as indicated by line 5—5 in Fig. 3; Fig. 6 is a vertical sectional view taken as shown by line 6—6 in Fig. 3; Fig. 7 is a horizontal view taken as shown by line 7—7 in Fig. 5; Fig. 8 is a horizontal sectional view taken along line 8—8 in Fig. 5; Fig. 9 is a view similar to Fig. 8 taken along line 9—9 in Fig. 6; Fig. 10 is a horizontal sectional view taken as indicated by line 10—10 in Fig. 5; Fig. 11 is an enlarged fragmentary view of the connection between the housing and cover taken as indicated by line 11—11 in Fig. 8; Fig. 12 is an enlarged fragmentary view of the supporting seat within the housing taken as indicated by line 12—12 in Fig. 9; Fig. 13 is an enlarged fragmentary view of the bell supporting structure shown in Fig. 5; Fig. 14 is a view partly in section of the link between the core and the bell supporting member taken as indicated by line 14—14 in Fig. 13; Fig. 15 is a sectional view of the bell supporting structure taken as indicated by line 15—15 in Fig. 13.

While I have shown and shall hereinafter describe certain embodiments of my invention, it is to be understood that it is capable of many modifications. Changes, therefore, in the construction and arrangement may be made without de-

parting from the spirit and scope of the invention as disclosed in the appended claims.

Fig. 1 illustrates a Christmas tree 16 having thereon a light strand 17 containing a plurality of light sockets for the reception of colored Christmas tree lights. An interrupter 18 is interposed in the wall socket supplying electricity to the strand and causes an intermittent flow of electricity to the light sockets in the strand. The interrupter may be a commercial type, either one that breaks the circuit or one that diminishes the voltage substantially and has a high resistance around the break point. The unit of this invention is adapted to be attached to one of the light sockets of the strand 17 as indicated generally at 19 in Fig. 1. When attached in this position, the bell will be rung with each intermittent surge of electricity to the unit. In general, the unit comprises a solenoid winding 20 having a core 21 operatively connected to a bell 22 so as to ring the bell with each activation of the solenoid. A housing 23 having an upper cover 24 and attaching means projecting from the cover is provided around the solenoid for supporting the unit on the limb of a Christmas tree or the like.

The solenoid winding 20 is made upon a nylon spool 25 having a projection 26 at one end which is provided with a metal cap 27 screw-threaded so that it may be received in the ordinary female light socket 28 of the strand of Christmas tree lights. Another type of electrical connection may be used if desired, such as a pronged male member with a corresponding female socket. The core 21 is movable coaxially within the spool 25 and upon energizing the solenoid the core is drawn into the spool.

A plate 30 is secured to the bottom of the spool 25 and has a pair of fingers 31 and 32 extending outwardly beyond the circumference of the solenoid. The fingers 31 and 32 are adapted to be received in seats 33 and 34 formed in the interior wall of the housing 23. As best seen in Fig. 9, the housing has a four-leaved clover cross sectional outline and the fingers of the plate 30 may be turned so as to miss contact with the seats, or as indicated in Figs. 6 and 7, may be positioned to engage the seats to support the solenoid within the housing. The walls of the housing are spaced from the solenoid in order that air may pass between them to cool the winding.

The cover 24 is of the same general cross-sectional shape as the housing 23, but of larger configuration. The cover has a central aperture 36 made to slip over the threaded member 27 on the spool 25. As best seen in Fig. 11, the cover is provided with spaced notches 37 for engagement

by corresponding projections 38 on the housing 23. As indicated in Figs. 5-7, the cover and housing are spaced apart when assembled so that air may escape between them. Once the unit is assembled, it is contemplated that the purchaser will have no occasion to take it apart. However, for convenience of assembly in manufacture, the units are provided with easily assembled parts.

The cover is molded with a pair of slots in its upper portion for the reception of base portions 42 and 43 of supporting arms 40 and 41. A split spring ring 44 is made to engage notches in the base portions 42 and 43 (Fig. 5) to hold the supporting arms securely within the housing. The arms are made of relatively thin spring steel and are provided with hooked portions 45 and 46 normally spaced apart as illustrated in Figs. 2 and 5, and normally disposed in the same plane but which may be pressed together to overlap the hooks around a limb 48 as illustrated in Fig. 2. To engage the hooks on a limb, the arms are positioned with the limb between them after which they are pressed together to overlap the hooks. The limb is placed in the overlapping hooks (Fig. 5) after which the arms are released to bind against the limb. In this position, the hooks each have two points of contact with the limb and hold the unit securely in upright position. There results a twisting engagement with the limb by the cooperative action of the hooks as illustrated in Fig. 2.

Novel means are provided for pivotally or swingably supporting the bell. Herein this means takes the form of a member 50, integral with plate 30, extending downwardly and at the side of the solenoid. As best seen in the detail of Figs. 13-15, a bell supporting member 51 is pivotally attached at one end to the member 50. The other end of the member 51 is connected by link 52 to the lower end of the core 21 of the solenoid. The bail 53 of the bell is rigidly attached to the bell and is provided with notches 55 and 58 at its apex. The member 51 is provided with a slot into which the apex of the bail fits with notch 58 engaging the sides of member 51 and a finger 54 being turned over into the notch 55. Thus the bell, its bail and member 51 are assembled to move together as a unit. The link 52 is formed as shown in Fig. 14 having similar halves on each side of member 51 and engaging the core. A projection 56 on the end of member 51 adjacent the link 52 prevents the link from swinging beyond the end of member 51. Thus, as illustrated in Fig. 5, the link 51 cannot get past the projection 56, preventing the core 21 from sliding out of the spool of the solenoid. Without this projection in the path of the link 52 the core would be able to drop out of the spool after each deenergization of the solenoid.

In operation the solenoid is energized drawing the core 21 upwardly into the spool 25. The clapper 57 on the bell 22 stays in the position illustrated mainly by its own inertia as the bell is swung about the pivot of the bell supporting member 51. By this arrangement the clapper strikes the bell both when the solenoid is energized and when it is deenergized. Moreover, with each impact of the bell with the clapper, the clapper is moved and upon falling back to its normal position strikes the bell to produce a secondary ringing.

Referring particularly to Figs. 2 and 5 of the drawings, it will be noted that the bell is mounted eccentrically of the solenoid. As the solenoid

is energized, the bell moves from the solid line position in Fig. 2 to the dotted line position in Fig. 2 upwardly toward the lower open end of the housing. This action is rather quick and forces air into the space between the housing 23 and the solenoid. In fact, the movement of the bell acts as a pump forcing air in and around the solenoid to cool it as it is operated.

To provide for fluctuations in the current supplied to the device, a conventional light 70 is connected in series with the solenoid 20. The light bulb is used to aid in maintaining the coil of the solenoid cool in operation. The lines 71 leading to the light 70 pass between the housing 23 and the cover 24 of the unit and are connected in series with the windings of the solenoid. The light takes part of the load from the solenoid and in addition acts in part as a regulator during line voltage fluctuations. It also adds to the attractiveness of the device by shining a light on the bell.

The housing and cover are generally constructed of plastic material and may be given a configuration suitable to pleasing design and to provide the air spaces around the solenoid as described above. The connections between the housing and cover provide easy assembly since the plastic material has some resiliency and the exertion of pressure thereon will cause sufficient bending to allow the pieces to be connected. The core is also easily assembled in the housing by turning the fingers to engage their respective seats. The cover holds the core within the housing and the supporting arms are rigidly attached to the housing to support the unit.

I claim:

1. An ornamental bell ringing unit comprising a solenoid having a movable core therein, a pivotally supported bell operatively attached to the core to cause the bell to move about its pivot upon movement of the core, a freely hanging clapper in the bell, a housing supporting the solenoid, a cover attached to the housing, and a pair of opposed semi-flexible arms attached to and extending outwardly from the cover, said arms having hooked portions at their free ends and being spaced apart when unrestrained whereby the unit may be fastened to a limb of a tree or the like and held in a predetermined fixed position.

2. An ornamental bell ringing unit comprising a solenoid having a spool provided with a male member adapted to be received in a corresponding female electrical socket, a molded housing about the solenoid having walls spaced therefrom and a plurality of supporting seats formed in the interior of said walls, a plate secured to the solenoid and having fingers receivable in said seats to support the solenoid within the housing, a bell pivotally supported adjacent one end of the solenoid, a clapper within the bell and a core movable axially within the solenoid and operatively connected with the bell to cause movement thereof with movement of the core.

3. The apparatus of claim 2 wherein the plate has an integral portion extending away from the solenoid for supporting the bell eccentrically of the solenoid and a bell supporting member is swingably attached to said portion.

4. An ornamental bell ringing unit comprising a solenoid adapted to be connected with an intermittent source of electrical energy, a core movable axially within the solenoid, a housing about the solenoid having walls spaced there-

from, means for supporting the solenoid in the housing, a cover attached to one end of the housing and having a cross-sectional configuration differing from that of the housing to provide air passage ways between the housing walls and the cover, and a pivotally supported bell at the other end of the housing operatively attached to said core, said bell being provided with a clapper.

5. In an electrical bell ringing unit having a solenoid provided with a movable core operatively attached to the bell to cause movement thereof and the bell having a clapper, cooling means for the solenoid comprising, a housing about the solenoid in spaced relation thereto, a bell supporting member pivoted at one end at a point to one side of the solenoid, a link securing the other end of said member to the core of the solenoid, and the bell being attached to the supporting member between the ends thereof whereby energizing said solenoid pulls the core into the solenoid and moves the bell toward the unit to force air into the space between the solenoid and housing.

6. A bell ringing unit comprising, a solenoid having means connecting it to an intermittent source of electrical energy, a core movable axially within the solenoid, a bell having a bail providing a loop externally and an eye internally for supporting a clapper, bell supporting means attached to said bail and extending laterally of the bell for pivotally suspending the bell from the solenoid, link means connecting said supporting means and the core and stop means for limiting the pivotal movement of the link around the bell supporting member to prevent the core from removing from the solenoid.

7. A bell ringing unit comprising a solenoid having means connecting it to an intermittent source of electrical energy, a core movable axially within the solenoid upon energization or deenergization thereof, means for supporting the unit in upright position, a bell having a clapper and a bail, a bell supporting member affixed to the bail and pivotally secured at one end below the solenoid and at one side thereof, a link connecting the other end of the member to the end of the core, said link having portions astride the bell supporting member, and an integral projection on said member positioned in the path of the link preventing movement thereof be-

yond the end of the member whereby the link and bell supporting member prevent the core from falling out of the solenoid upon deenergization thereof.

5. 8. A bell ringing unit having a clapper in the bell and comprising a solenoid having means connecting it to an intermittent source of electrical energy, a core movable axially within the solenoid upon energization or deenergization thereof, means for supporting the unit in upright position, a plate affixed to the lower end of the solenoid provided with a downwardly extending portion adjacent the side of the solenoid, a bell supporting member having one end pivotally connected to said downwardly extending portion, a link connecting the other end of said member to the core, a bell having a bail provided with a notch in one side thereof, said bell supporting member being provided with a slot for receiving said bail and a finger adapted to engage said notch to secure the bell to the member and a projection on said member positioned in the path of the link limiting movement of the link about the end of the member whereby said core is retained in the solenoid during operation of the unit.

9. An ornamental bell ringing unit having a clapper in the bell and comprising a solenoid connected with an intermittent source of electrical energy, a housing about the solenoid for supporting the same, said housing being spaced from the solenoid to provide air passages between said walls and solenoid, means for removably supporting the unit in upright position and a core movable within the solenoid upon energization or deenergization of the solenoid, said core being operatively connected with a bell to ring the same upon movement of the core.
